ELECTRONIC TIMING APPARATUS

E. Craig Thomson, Boston, Mass., assignor to
 Photoswitch, Incorporated, Cambridge, Mass.,
 a corporation of Massachusetts

Application August 23, 1944, Serial No. 550,808

4 Claims. (Cl. 250—27)

1

This invention relates to electronic timing apparatus and especially to apparatus of that type wherein a preset timing operation becomes effective upon separation of the timed unit from a setting unit.

Some of the main objects of the invention are to provide timing apparatus which will automatically initiate a timing cycle when a timed portion of the apparatus is separated from a setting portion thereof; to provide such apparatus which can be preset while positively preventing any danger of the timing function from becoming effective prior to the intended starting thereof; to provide timing apparatus of this type which permits the safe presetting of several timed units with the aid of a single setting unit; to provide a timing device that permits the safe setting of a timer with the timing to start solely upon disconnection of setting and timing units and not possibly prior to that step; to provide apparatus of this type with separable timing and setting units wherein the timing unit contains provisions that automatically prevent any possibility of its energization prior to release from the setting unit after performance of the setting operation; to provide apparatus of this type whose timing circuit can be accurately calibrated and whose timing period can be accurately set with simple means; and to provide apparatus of this type which is simple, rugged and inexpensive and yet reliable and exact, and hence suitable for uses such as the setting of the time for explosion of bombs by means of a setting control panel permanently mounted in an airplane, with the timing commencing upon separation of the bomb from the panel, but with any possibility of premature ignition excluded.

For that purpose the invention proposes, in one of its aspects, the use of a controlling electron discharge tube that, in addition to a control electrode for initiating the timed operation has a second control electrode that absolutely locks the tube so long as the timing unit is connected to the setting unit and for a predetermined time thereafter.

Other objects, aspects and features of the invention will be more fully apparent from the following description and reference to the accompanying circuit diagram.

In the drawing, a current source such as battery 10 supplies wires A1 and B1 which lead to switch contacts 1 and 2. An electron discharge tube T with anode a, cathode k, grid g, screen s, and heater h is connected between wires A1 and B1. An operator device such as relay S with magnet L and magnet-operated switch s1 is connected in the load circuit of tube T.

2

Relay S may operate any desirable controlled device indicated at 20, for example igniting means if the apparatus is to be used for the timed explosion of bombs.

5 Connector contacts 1, 2, 3 and 4 may be the plug in portions of a switching device having corresponding contact receptacles 11, 12, 13, 14. Contacts 1, 2, 3, 4 may be fastened to a frame or housing indicated at I and containing the controlled 10 or timing unit, whereas receiving contacts 11, 12, 13, 14 may be mounted on a control box or panel or setting unit indicated at II. The respective connections may be opened by separating unit I from unit II.

15 The setting unit II contains between supply wires A2 and B2 which are connected to contacts 11 and 12, respectively, a potential apportioning device, for example resistor R1 with adjustable tap b.

20 A timing network extends through both units and may consist of a capacitor C1 and a resistor R2 connected in series between grid g and adjustable tap d of a resistor R3 connected across wires A1, B1, a resistor R4 connected across capacitor C1, and a connection leading from junction point e through wire 16, contacts 4 and 14, normally open switch s2 and resistor R5 to tap b of resistor R1.

25 A blocking network may consist of a resistor R6 and a capacitor C6 connected in series between wires A1 and B1, a connection 17 from point f between R6 and C6 to screen grids of tube T and a connection from f through wire 18, contacts 3 and 13 and wire 19 to conductor B2 of unit II.

30 This arrangement operates as follows:

Assuming that the timed unit I is joined to the setting unit II through contacts 1—11, 2—12, 3—13 and 4—14, and that switch s2 is open, the 35 desired time interval is selected by means of adjustable tap b of resistor R1 which may be calibrated in terms of time intervals within the range for which the circuit is dimensioned.

40 At this stage of the operation, control grid g has a positive bias but tube T is nevertheless retained nonconductive by screen grid s, which is through 17—f—18—3—13—B2 connected to cathode k and therefore blocks the tube.

45 After selection of the timing interval by means of slider b, switch s2 is closed. Current now flows from supply wire A1 through grid circuit A1—A2—R1—b—R5—s2—14—4—16—e—C1—g—k—B1 and this grid current charges condenser C1, the charge being determined primarily 50 by the position of tap b. The resistance of R4 is

preferably quite high, but that of R5 rather low although high enough to limit the grid current to a safe value.

The resistance of R2 is intermediate those of R4 and R5 so that with 4-14 closed, the current in circuit A1-1-11-A2-b-R5-s2-14-4-16-e-R2-d-B produces a voltage drop mainly in R2. Hence points e and b are essentially of the same potential and capacitor C1 charges approximately to the potential difference between points b and B1. This charge on C1 about cancels the voltage drop across R2 plus that from d to B1.

If the timed unit I is now disconnected from setting unit II, for example by dropping the bomb to which unit I is attached, contact is broken at 1, 2, 3, 4. The potential difference between e and d becomes zero and only the drop from d to B1 counteracts the charge on C1. This means that the positive side of capacitor C1, namely that of point e drops to a value determined by tap d and this change drives the control grid g very far negative.

Simultaneously, contact is severed at 3-13 and the screen grid s separated from its cathode. The tube is now blocked by its control grid, during the timing cycle which now begins and in addition by the screen grid during a shorter safety interval beginning at the same time.

The timing cycle is determined by resistor R4 and capacitor C1, the voltage to which C1 is charged and also by the position of tap d on R2. As capacitor C1 discharges, grid g becomes less negative until tube T begins to conduct and energizes relay magnet L. This will occur when the charge of C1 has become sufficiently low to approximate the voltage drop from d to B1, which is the reason why the position of d becomes a means for accurately adjusting or calibrating the timing period.

By means of tap d the device can be calibrated for energization of the relay at a given fixed lower limit of the charge on capacitor C1, the proper setting of this tap compensating for variations in tube and relay characteristics.

The blocking network with circuits s-17-f-C6-B1 and f-18-3-13-19-B2 provides a safety feature. As pointed out above, the screen grid is on cathode potential so long as connection 3-13 is closed. After unit I is detached from setting unit II and switch 3-13 is open, condenser C6 assumes the blocking function, so that the tube cannot become conductive during a certain minimum time interval, regardless of the control grid potential, so that there is less chance of premature ignition if other circuit elements should unsafely fail. This safety time interval is predetermined, for example by adjusting condenser C6, to be long enough to permit separation by a safe distance of the timed unit I, but of course to be shorter than the timing period effected by capacitor C1.

It will now be evident that the timing device according to the present invention not only provides a safety period due to the function of the safety circuit with screen grid s and capacitor C6, but that this circuit furthermore keeps the relay safely deenergized during the charging of C1. Without this provision, a special normally open safety contact would have to be provided, to be closed at the beginning of the timing period. Evidently, a circuit which only requires contacts to be opened at the beginning of the timing is of distinct benefit, since such equipment is inherent in devices of this type where one element is released for ignition.

It should be understood that the present dis-

closure is for the purpose of illustration only and that this invention includes all modifications and equivalents which fall within the scope of the appended claims.

5 I claim:

1. In electric timing apparatus the combination of: a controlled unit comprising a current source; an electron discharge device having two control electrodes and an output circuit connected to the respective terminals of said source; four connector contacts; connections from said terminals to a first and a second of said connector contacts; a blocking network including a resistor and a capacitor connected in series between said terminals, a connection from a tap intermediate said resistor and said capacitor to one of said electrodes and a connection from said tap to a third one of said connector contacts; and a timing network including a voltage-apportioning means having an adjustable tap and being connected across said terminals, a capacitor and a resistor connected in series between said adjustable tap and the second electrode, a resistor in parallel to said capacitor and a connection from said adjustable tap to the fourth connector contact; with a setting unit comprising four contact receptacles; a potential-apportioning means whose ends are connected to a first and second of said contact receptacles and which has an adjustable tap; a connection from a third of said contact receptacles to one end of said second apportioning means; and a normally open switch connected in series between said second tap and said fourth contact receptacle; said connector contacts being adapted for connection with and substantially simultaneously separation from correspondingly numbered ones of said contact receptacles.

2. Electric timing apparatus comprising a current source; an electron discharge device having two control electrodes and an output circuit connected to the respective terminals of said source; a first and a second potential-apportioning means connected to said source; a blocking network including a safety resistor and a capacitor connected in series between said terminals, a connection from a tap intermediate said resistor and said safety capacitor to one of said electrodes, and a connection bridging said safety capacitor; a timing network including a timing capacitor and a resistor connected in series between an adjustable tap of said first potential apportioning means and the second electrode, a resistor in parallel to said timing capacitor and a connection from an adjustable tap of said second potential apportioning means to said timing capacitor; a normally open switch connected in series between said last-named tap and said timing capacitor; and connector switches between the ends of said second potential-apportioning means and said source, between said normally open switch and said timing capacitor, and in said bridging connection, said connector switches being adapted for substantially simultaneous opening.

3. In electric timing apparatus the combination of: a controlled unit comprising a current source; an electron discharge device having a first and a second control electrode and an output circuit connected to the respective terminals of said source; four connector contacts; connections from said terminals to the first and second of said connector contacts; a blocking network including a safety capacitor connected between said terminals, a connection from one side of said capacitor to one of said electrodes and to

the third of said connector contacts; and a timing network, connected between said second electrode and the fourth of said connector contacts; with a setting unit comprising four contact receptacles; a potential-apportioning means whose ends are connected to the first and second of said contact receptacles; a connection from the third of contact receptacles to one end of said potential apportioning means; and a normally open switch connected between said potential apportioning means and the fourth of the contact receptacles; said connector contacts being adapted for connection with and substantially simultaneous separation from correspondingly numbered ones of said contact receptacles.

4. Electric timing apparatus comprising a current source; an electron discharge device having two control electrodes and an output circuit connected to the respective terminals of said source; a blocking network including a safety capacitor connected between said terminals, a connection from one side of said capacitor to one of said electrodes and a connection bridging said safety capacitor; a timing network including a voltage-apportioning means connected across said ter- 25

minals, a timing capacitor connected between said voltage-apportioning means and the second electrode, a resistance connected in parallel with said timing capacitor and a normally open switching means between said voltage apportioning means and said timing capacitor; and connector switches between the two sides of said voltage apportioning means and said source, in said bridging connection and between said switching means and said capacitor.
